UNITED STATES PATENT OFFICE.

JOHN O. CARREY, OF ST. LOUIS, MISSOURI, ASSIGNOR TO CARREY-MORSE ENGINEERING COMPANY, OF ST. LOUIS, MISSOURI, A CORPORATION OF MISSOURI.

PRESSURE-REDUCING DEVICE.

Application filed May 22, 1923. Serial No. 640,633.

This invention relates to new and useful improvements in pressure reducing devices, and the objects of the invention are to provide a simple and efficient device adapted to establish communication between the high pressure side and the low pressure side of a fluid pressure system and to provide a device of the class described which is of simple and durable construction, automatic in its action, and can be manufactured at low cost.

5 Further objects of the invention are to provide a valve adapted to close the high pressure inlet and to provide a pressure operated diaphragm for controlling said valve and closing said high pressure inlet at the appropriate time.

10 Still further objects of the invention are to provide means for regulating the operation of said valve and an improved means 15 for sealing the access to said adjusting means and said diaphragm.

15 With these and other objects in view, my invention consists in certain novel features of construction and arrangement of parts herein after more fully described and claimed, and illustrated in the accompanying drawings, in which—

20 Figure 1 is a vertical cross section through the device.

25 Figure 2 is a horizontal cross section taken on line 2—2 of Figure 1.

30 Figure 3 is a horizontal cross section taken on line 3—3 of Figure 1.

35 Figure 4 is a vertical section through a modified form of the pressure reducing device.

40 Figure 5 is an enlarged sectional detail view of the valve operating mechanism of the device.

45 Figure 6 is a horizontal section taken on line 6—6 of Figure 4.

50 Figure 7 is an enlarged perspective view of the adjustable valve stem supporting member.

55 Figure 8 is an enlarged perspective view of the valve stem.

60 Figure 9 is an enlarged perspective view of the valve stem locking member.

65 The pressure reducing device disclosed in this application is particularly designed for use in connection with refrigerating systems, but is equally as well adaptable for use in any fluid pressure system.

70 Referring by numerals to the accompanying drawings, 10 indicates a housing in the

form of an inverted truncated cone, the lower end of which is closed by a yielding wall or diaphragm 11. The upper end is formed with an outwardly presented circular flange 12 to which is secured an annular 60 flange 14 of a diaphragm 15 which closes the upper end of housing 10. A convex plate 16 is arranged above diaphragm 15 and spaced therefrom, and the edge thereof is folded over flanges 12 and 14 as indicated 65 at 17 and serves to form an air-tight seal. The inturned edge 17 may be secured in position on housing 10 in any suitable manner and preferably by soldering, as indicated at 18.

70 A high pressure chamber 19 is formed by diaphragm 15 and plate 16 and an intermediate chamber 20 is formed in housing 10 by diaphragms or yielding walls 11 and 15. A circular housing 21 is secured to the lower 75 end of housing 10 and has formed therein a receiving chamber 22. Leading into this chamber is a high pressure inlet connection 24 having a ball valve 25 which is designed to close the communication between the inlet connection 24 and chamber 22 when pressure in chamber 19 reaches a predetermined degree.

75 A sleeve 26 is disposed in chamber 20 of housing 10 and the ends of said sleeve are secured to diaphragms 11 and 15. This sleeve is internally threaded for the reception of a threaded stem 27, the lower end of which is reduced in diameter as indicated at 28 and is adapted to bear on ball valve 25. Stem 27 is provided with a longitudinal bore or opening 29, the upper end of which communicates with chamber 19 and the lower end of which opens into the receiving chamber 22. The stem 27 is adjustable in sleeve 26 in order to provide a proper operating clearance between the lower end of extension 28 and ball valve 25. When stem 27 has been properly adjusted it is locked in position by a screw 30 which is seated in the upper end of sleeve 26 and bears on the upper end of stem 27. This screw has a longitudinal bore so as not to disturb the communication between the bore of stem 27 and chamber 19.

105 The access to chamber 19 and screw 20 and stem 27 is obtained through an opening formed in plate 16 in alignment with said stem. The opening is preferably formed by means of a tubular section 31 which is 110

arranged in plate 16 and is preferably held in position thereon by having its ends crimped against said plate. Sleeve 31 is provided with an interior thread in which is 5 screw-seated a plug 32. This plug is provided with an inverted cup-shaped member 34 having a gasket 35 of lead or other suitable material arranged therein so that when the plug is screwed in position the upper 10 end of tubular section 31 is forced into the gasket 35 and seals chamber 19 to the atmosphere.

In the operation of the device, the inlet connection 24 is connected to the high pressure side of the fluid system and the outlet connection 23 is connected to the low pressure side of the system. The fluid is admitted under high pressure through connection 24 into the receiving chamber 22 15 unseating ball 25 from its seat in inlet connection 24. A portion of the fluid passes through bore 29 into the high pressure chamber 19. When the pressure in chamber 19 reaches a predetermined degree, diaphragm 15 is caused to move inwardly thereby forcing stem 27 downwardly so that the lower end of extension 28 forces ball 25 against its seat, thereby closing the communication 20 between the inlet connection 24 and receiving chamber 22. The fluid contained in receiving chamber 22 is discharged through outlet connection 23 and the fluid contained in chamber 19 is drained therefrom through bore 29 into the receiving chamber 22. When 25 the pressure in chamber 19 falls below a predetermined degree diaphragm 15 moves to its normal position causing sleeve 26 and stem 27 to move upwardly thereby moving the lower end of extension 28 away from ball 25. As soon as extension 28 is moved out of contact with ball 25 the pressure in the inlet connection 24 will again unseat ball 25 thus permitting fluid to flow into the receiving chamber 22 and repeating the cycle 30 of operation just described.

The wall 11 is yielding so as to permit the longitudinal movement of sleeve 26 and stem 27 when diaphragm 15 is operated and the diameter of this wall 11 is proportionately 35 small relative to the diameter of diaphragm 15 so that the pressure exerted in chamber 19 against diaphragm 15 is sufficient to overcome the pressure exerted against diaphragm 11 in chamber 22. Intermediate chamber 40 20 in housing 10 is preferably filled with fluid under pressure which is sufficient to strengthen diaphragms 11 and 15 but not great enough to interfere with the operation of diaphragm 15. When chamber 20 45 has been placed under pressure the opening thereto is closed in any suitable manner as by a drop of solder, as indicated at 36.

In the modified form illustrated in Figures 4 to 9, only one diaphragm member is 50 used and a coiled spring is utilized for main-

taining the diaphragm in normal or open position. An inverted cone-shaped casing 38 is provided in its upper end with a diaphragm 39 thereby forming a pressure chamber 40. A fitting 41 is secured to the top wall 42 of casing 38 and is provided with an outlet connection 43 for discharging the fluid from pressure chamber 40. Fitting 41 is provided with a removable plug 44 whereby access may be had to the interior of the casing for adjusting purposes. The lower end of casing 38 has secured thereto a tubular fitting 45 in the lower end of which is threaded an inlet connection 46 controlled by a valve 47 seated therein. The upper end of tubular fitting 45 extends upwardly within casing 38 and slidably arranged therein is the lower end of a sleeve 48, the upper end of which is secured to diaphragm 39. This sleeve is internally threaded for receiving a short tubular section 49. A valve stem 50 extends downwardly through sleeve 48 and tubular fitting 45 and is provided with an extension 51, the lower end of which is adapted to engage the upper end of valve 47. The upper end of said valve stem is provided with an enlarged head 52 which is exteriorly threaded for engagement with the internal thread of tubular section 49.

A plug 54 is screw-threaded in said tubular section and is designed to engage the upper end of the enlarged portion 52 and lock valve stem 50 in position. Valve stem 50 is provided with a laterally opening bore 55 which communicates with a longitudinally disposed duct 56 formed in said stem and plug 54 is provided with a longitudinally disposed aperture whereby fluid may pass from the inlet connection 46 through duct 56 upwardly into the pressure chamber 40. A coiled spring 56^a is arranged in fitting 45 and engages the lower end of slidably tubular member 48 and tends to maintain diaphragm 39 in its expanded or normal position. When in this position the lower end of extension 51 is moved away from valve 47 thereby permitting said valve to be unseated by the fluid pressure whereby fluid may pass from the inlet connection 46 through duct 56 into pressure chamber 40. When the pressure in this chamber reaches a predetermined degree, diaphragm 39 is operated causing sleeve member 48 to move downwardly against the influence of spring 56^a and compressing the latter and causing the extension 51 to engage valve 47 and seat it in inlet connection 46 thereby closing the latter.

A fluid contained in pressure chamber 40 is discharged through outlet connection 43 and when the pressure in said chamber falls below a certain degree, diaphragm 39 assumes its normal position, thereby releasing valve 47 and permitting fluid under pressure to enter pressure chamber 40.

In order to maintain a fluid tight seal between the stationary fitting 45 and the movable sleeve 48 bellows 57 is arranged in casing 38 and the upper end of said bellows is 5 fixed to sleeve 48 while the lower end is secured to fitting 45.

The device may be regulated by adjusting tubular section 49 in sleeve 48 and by adjusting valve stem 50 in tubular section 49.

- 10 In order to prevent movement of tubular section 49 when the enlarged head 52 of valve stem 50 is turned, the pitch of the internal thread of tubular section 49 and of the thread on the enlarged head 52 is different 15 from the pitch of the external thread of tubular section 49. In the present instance, the internal thread of tubular section 49 is finer relative to the external thread of said section, which external thread is comparatively 20 coarse. Thus the accidental displacement of valve stem 50 is safeguarded against and I am enabled to obtain accurate adjustments.

A pressure reducing device of my improved construction contains but few parts thereby eliminating the danger of the device getting out of order, is adjustable so as to regulate the pressure, and is automatic in its action.

30 I claim:

1. A pressure controlling device comprising a casing provided at one end with a high pressure chamber and at its opposite end with a receiving chamber, said chambers being provided with yielding inner walls of proportionate diameter, a sleeve secured at its end to said yielding walls, an outlet connection leading from said receiving chamber, an inlet connection leading to said receiving chamber, a valve controlling one of said connections, and a valve stem adjustably arranged in said sleeve and in operative engagement with said valve, said stem being provided with a bore connecting said chambers whereby when fluid pressure in said pressure chamber reaches a predetermined degree said yielding walls cause the stem to operate said valve.

2. A pressure controlling device comprising a casing provided at one end with a high pressure chamber and at its opposite end with a receiving chamber, said chambers being provided with yielding inner walls of proportionate diameters, a sleeve secured at its end to said yielding walls, an outlet connection leading from said receiving chamber, an inlet connection leading to said receiving chamber, a valve controlling one of said connections, a valve stem adjustably arranged in said sleeve and in operative en-

gagement with said valve, said stem being provided with a bore connecting said chambers whereby when fluid pressure in said pressure chamber reaches a predetermined degree said yielding walls cause the stem to operate said valve, and means for locking the stem in adjusted position.

3. A pressure reducing device comprising a casing provided at one end with a high pressure chamber and at its opposite end with a receiving chamber, the inner walls of said chambers being yielding and of different diameters, an intermediate chamber arranged in said casing and adapted to be placed under suitable fluid pressure to partially balance said yielding walls, a sleeve secured at its ends to said yielding walls, a stem screw-seated in said sleeve and provided with a passageway for connecting said receiving chamber and said high pressure chamber, a low pressure outlet connection in said receiving chamber, a high pressure inlet connection in said receiving chamber, and a ball valve arranged in said inlet connection for controlling the admission of fluid to said receiving chamber and operable by said stem.

4. A pressure reducing device comprising a casing provided with a pressure chamber and a receiving chamber of unequal diameters, each of said chambers being provided with an inner yielding wall or diaphragm, a tubular section secured at its ends to said walls, an adjustable stem in said section and provided with a duct for conveying the fluid from the receiving chamber to said pressure chamber, an inlet connection for said receiving chamber and a valve for closing said inlet connection and operable by said stem when the diaphragm in said pressure chamber is actuated.

5. A pressure reducing device comprising a casing provided with a pressure chamber and a receiving chamber of unequal diameters, each of said chambers being provided with an inner yielding wall or diaphragm, a tubular section secured at its ends to said walls, an adjustable stem in said section and provided with a duct for conveying the fluid from the receiving chamber to said pressure chamber, an inlet connection for said receiving chamber and a valve for closing said inlet connection and operable by said stem when the diaphragm in said pressure chamber is actuated, and means in the outer wall of said pressure chamber for providing access to said adjustable valve stem.

In testimony whereof I hereunto affix my signature this 2nd day of April, 1923.

JOHN O. CARREY.
